RECORDING MEANS FOR BUSY TELEPHONE LINES.

Application filed June 9, 1926, Serial No. 114,717, and in Great Britain July 9, 1925.

This invention relates to telephone exchange systems and particularly to recording arrangements for such systems.

While it is customary for business houses as well as other associations and individualsto subscribe for as many telephone lines as seem sufficient for their needs, it is often difficult to know whether the number subscribed for is actually great enough since no record is made of the number of times a line is tested and found busy.

It is the object of the present invention to record the number of times a connection is attempted with a line while it is busy.

15 A feature of the invention is the provision of a recording device responsive to the reduced potential produced on the test terminal of a subscriber's line by an attempted connection therewith while said line is busy.

20 A further feature of the invention is the use of a vacuum tube to render the above mentioned reduced potential effective to operate a recording device.

In the disclosed embodiment of the invention, the test terminal of a subscriber's line is connected with the grid of a vacuum tube forming a part of the recording device. When the line is idle or busy with a call, the potential of the grid is sufficient to prevent 30 current flow in the vacuum tube but when a second call is attempted the potential is reduced to such a point that current will flow in the tube. This current is assisted by a condenser discharge to cut off the current flow in a second vacuum tube releasing a relay and operating a meter.

The drawing shows a subscriber's line appearing in multiple terminals of a line finder and a plurality of final selectors. A portion 40 of the connecting apparatus in each case is indicated diagrammatically. The apparatus within the broken rectangle comprises the recording device which may be connected with any subscriber's line.

45 The recording device 100 consists essentially of a meter 108 together with the controlling circuits therefor. These controlling circuits comprise a pair of vacuum tubes 101 and 102 and a relay 103 shunted by condenser 104. Battery 105 is used for supplying the filaments of the vacuum tubes and is lower in potential and opposite in polarity to batteries 106 and 107 which supply potential

to the plates of the vacuum tubes. No attempt has been made to indicate the relative 55 potentials of the batteries. The subscriber's line 1 is shown together with the multiple terminals in which it appears in the final selectors 2 and 3 and line finder 4.

As indicated above, this circuit makes use 60 of the change in potential of the subscriber's test terminal. The potential of this terminal may have at different times any one of four values which occur under the following circumstances:

A—subscriber's line free.

B—subscriber's line busy.

C—busy subscriber's line tested.

D—metering of completed call.

When a subscriber's line is free, the sleeve 70 terminal 6 will have the full potential of the battery since no current is flowing. When the subscriber's line is in use, say with final selector 2, relay 5 will be operated and a circuit will be completed through that relay 5 to 75 ground. In consequence, the potential of the sleeve terminal 6 will be reduced. A similar condition arises when substation 1 is busy as a calling line. Ground is connected to the line finder terminal 13 through a resistance, 80 not shown, as soon as the line has been associated with a selector. If a second final selector, such as selector 3, tests the line while it is busy, ground will also be connected to terminal 6 through relay 7 and resistances 8 and 85 9. This will further reduce the potential of terminal 6. The fourth condition enumerated above occurs when the line has been busy as a calling line. If the outgoing call has 90 been completed, apparatus (not shown) will be actuated to connect battery 10 to the terminal 6 through the line finder for the purpose of operating meter 11. It will be noted that battery 10 is oppositely polarized to the operating battery of cut-off relay 12. It is 95 also of greater potential in order to overcome that connected to the message register. For a description of the operations which give rise to these conditions, reference may be made to U. S. Patent 1,365,269, granted to L. Polinkowsky, January 11, 1921.

When it is desired to test whether a line or group of lines are sufficient, the recording device 100 is connected with the test terminal 6 of the subscriber's line or the last line of 105 the group in any desirable manner. The fila-

ment battery switch 109 is closed and the filament current adjusted by means of ammeter 110 and adjustable resistance 111. Jack 112 is arranged to permit the inclusion or omission of ammeter 110 as desired. Jacks 114 and 115 also permit the checking of the plate voltage or the space current if desired. The readings of service meter 11 and meter 108 are noted at the beginning of the period during which the line is to be under observation

With the subscriber's line free, full battery potential will be present on grid 113. This potential being much more negative than that of the filament battery 105, no current will be permitted to flow between filament 116 and plate 117. Grid 120 of the second vacuum tube 101 is connected to the positive side of filament 118 and will, therefore, be less negative than the filament so that current will flow between filament 118 and plate 119. Relay 103 which is included in this circuit is operated, opening the circuit of meter 108. This steady condition continues as long as the line 1 is free.

When a connection is established with the subscriber's line 1, either as a calling line or as a called line, ground through a resistance is connected to the test terminal of the line, and, due to the current drain through said resistance, the potential of terminal 6 is reduced. The grid 113, therefore, becomes less negative with respect to the filament but the characteristics of the tube 102 are such that the steady condition, as above described, still persists and relay 103 remains operated.

When now a second final switch, such as final selector 3, attempts a connection to subscriber's line 1, ground through relay 7 and resistances 8 and 9 is connected to the test terminal of the line multiplied before switch 3. This further reduces the negative potential of terminal 6, and in consequence, of grid 113. This reduction is sufficient to permit current to flow between filament 116 and plate 117. The condenser 121 which is connected with plate 117 now discharges through resistance 122, increasing the negative potential of grid 120 to such a point that the current flow between filament 118 and plate 119 is substantially cut off. Relay 103 is, therefore, deenergized and closes the circuit of meter 108 causing that meter to operate. As soon as the discharge from condenser 121 ceases, a second steady condition is established, relay 103 is reoperated and meter 108 deenergized. Since the line is busy, relay 7 will not be operated and after a short interval the final selector will be disconnected from the terminals of line 1. As soon as the circuit of test relay 7 is open, grid 113 again becomes more negative than filament 116 and current ceases to flow through tube 102. Condenser 121 now charges slowly through resistance 123. The charging current through resistance 122 further reduces the negative

potential of grid 120, thus strengthening the plate current through relay 103 and holding that relay operated. When the condenser becomes fully charged, the first steady condition is again established.

On the release of a completed outgoing call, a positive battery 10 is connected to the multiple terminal 13 in the line finder, operating service meter 11. This positive battery will make the terminal 6, and consequently grid 113, positive also. The condenser 121 will be discharged as above described and meter 108 will be operated.

It is apparent, from the foregoing description, that meter 108 will record all those completed connections recorded by service meter 11 as well as attempted connections to the line when the line is busy. From these records the number of ineffective calls, due to the line being busy, may be obtained.

Although the invention has been disclosed and described in connection with an automatic telephone system, it is clearly well applicable to manual systems. In such a manual system it would only be necessary to arrange that the recording apparatus 100 respond to the usual manual busy test which occurs when the operator tests the sleeve of the line jack with the tip of her calling plug. Since the meter and cut-off relay of a manual line are very often connected to ground, a suggested arrangement would be the insertion of a high resistance sensitive relay in the conductor 124 which would be operated upon the establishment of a connection to extend conductor 124 to grid 113. It is also clear that other methods of coupling between the vacuum tubes could be used.

What is claimed is:

1. In a telephone system, lines, a recording device associated with one of said lines, means for interconnecting said line with a second line, means whereby an attempt may be made to connect a third line with said first line, and vacuum tube controlled means for recording said attempted connection.

2. In a telephone system, lines, a test terminal individual to one of said lines, means for interconnecting said line with a second line, means whereby an attempt may be made to connect a third line with said first line, means for supplying characteristic potentials to said test terminal when said first line is free, when busy, and when a second connection is attempted, a recording device, means for associating said device with said test terminal, and means responsive to the potential applied to said test terminal when a second connection is attempted to record said attempted connection.

3. In a telephone system, lines, a test terminal associated with one of said lines, means for interconnecting said line with a second line, means whereby an attempt may be made to connect a third line with said intercon-

nected first line, means for applying successively reduced potentials to said test terminal when said first line is free, when busy, and when a second connection is attempted, a recording device, means for associating said device with said test terminal, and means in said recording device responsive to the reduced potential applied to said test terminal by said attempted connection to cause the recording of said attempted connection.

4. In a telephone system, lines, a recording device associated with one of said lines, means for interconnecting said line with a second line, means whereby an attempt may be made to connect a third line with said interconnected first line, a meter in said recording device, and means responsive to said attempted connection to create a momentary condenser discharge current whereby said meter is operated once only.

5. In a telephone system, lines, a test terminal associated with one of said lines, means for interconnecting said line with a second line, means whereby an attempt may be made to connect a third line with said interconnected first line, means for applying potential to said test terminal when said first line is free, means for reducing said potential when said first line is interconnected with another line, means for further reducing said potential when said second connection is attempted, a recording device, means for associating

ciating said device with said test terminal, a meter in said recording device, means in said recording device responsive to said further reduction of potential to produce a momentary current and means responsive to said momentary current to operate said meter.

6. In a telephone system, lines, a test terminal associated with one of said lines, means for interconnecting said line with a second line, means whereby an attempt may be made to connect a third line with said interconnected first line, means for applying potential to said test terminal when said first line is free, means for reducing said potential when such line is interconnected with another line, means for further reducing said potential when said second connection is attempted, a recording device including a vacuum tube, means for applying said potentials to the grid of said vacuum tube, a meter in said recording device, means associated with said vacuum tube whereby said further reduction of potential produces a momentary current and means responsive to said momentary current to operate said meter.

In witness whereof, we hereunto subscribe our names this third day of May A. D. 1926.
